(57) CLAIM

The ornamental design for a kitchen cabinet as shown and described.

DESCRIPTION

FIG. 1 is a front, right and top perspective view of a kitchen cabinet showing my new design;

FIG. 2 is a front elevational view thereof;

FIG. 3 is a rear elevational view thereof;

FIG. 4 is a left view thereof;

FIG. 5 is a right view thereof;

FIG. 6 is a top plan view thereof;

FIG. 7 is a bottom plan view thereof;

FIG. 8 is a rear, left and bottom perspective view thereof;

FIG. 9 is another front, right and top perspective view in a different configuration; and,

FIG. 10 is an enlarged view of a portion labeled as 10 on FIG. 9.

The long dash-short dash broken lines depict enlargement boundaries that form no part of the claim.

1 Claim, 10 Drawing Sheets
